UNITED STATES PATENT OFFICE.

GEORGE A. SCHICK, OF CAMDEN, NEW JERSEY, ASSIGNOR TO FERDINAND KELLER, JR., OF PHILADELPHIA, PENNSYLVANIA.

MACHINE FOR PLUGGING LEATHER.

1,368,059.

Specification of Letters Patent.

Patented Feb. 8, 1921.

Application filed March 1, 1919. Serial No. 280,159.

To all whom it may concern:

Be it known that I, GEORGE A. SCHICK, a citizen of the United States, residing in Camden, New Jersey, have invented Machines for Plugging Leather, of which the following is a specification.

One object of this invention is to provide a substantial, simple and inexpensive machine for forming plugs of thread or equivalent material, in leather or other soles or the like, in order to strengthen or reinforce them, with a view to increasing their useful life;—the invention particularly contemplating a novel combination of parts for forming such reinforcing plugs from a single thread.

It is further desired to provide a machine for inserting a single thread in a body of sheet material to form lines of reinforcing plugs having heads at or immediately adjacent one face of said material;—the arrangement and operation of the parts of said machine being such as to require the minimum number of parts while being compact and of such a nature as will not easily get out of order or require frequent repairs.

I further desire to provide a machine of the above noted type with a novel form of holding awl and stripper whereby it shall be possible to properly manipulate a single thread during its formation into a series of reinforcing plugs or stitches in a body of sheet material.

These objects and other advantageous ends I secure as hereinafter set forth, reference being had to the accompanying drawings, in which,

Figure 1 is a fragmentary sectional perspective of a piece of sheet material showing the reinforcing plugs which my machine is designed to insert;

Figs. 2 and 3 are respectively front and side elevations, the first being partly in section, illustrating the various parts constituting my invention in the positions occupied at one point in their cycle of operation;

Figs. 4—5, 6—7, 8—9 and 10—11 are respectively front and side elevations similar to Figs. 2 and 3, further illustrating the operation of my machine;

Fig. 12 is a plan of the parts above the thread plate, showing them in the positions occupied in Fig. 6; and

Fig. 13 is a plan showing the parts under 55 the thread plate, also in the positions occupied in Fig. 6.

In the above drawings 1 represents the thread plate of a sewing machine, above which are mounted a thread guide 2, a 60 presser foot 3, a thread thrower 4 and an upper awl 5;—the presser foot being carried on a vertically reciprocable bar 6 whereby it may be raised or lowered at will.

The thread guide 2 is rigidly mounted 65 and remains at all times in the same position, while the awl 5 has an intermittent vertical movement from the extreme upper position shown in Fig. 3 to the extreme lower position shown in Fig. 7. The thread 70 thrower has an oscillatory movement in a vertical plane across the general line of the presser foot and at its lower end is extended at right angles away from the bar 6, as indicated at 7, having a notch or recess 75 (Fig. 12) for receiving a thread α running from the eye 9 of the thread guide to the work operated on.

The thread thrower 4 is so mounted and its lateral extension is so shaped that when 80 swung from one extreme position (Fig. 6) to the other (Fig. 2), it engages and draws a portion of the thread α in a substantially horizontal line from the thread guiding eye 9. The latter is formed in an angular 85 finger 10 carried in a substantially horizontal plane at the lower end of a vertical rod 2. A take-up arm 4 is engaged by the thread before it enters the thread guide and is actuated periodically in the usual manner 90 by well known means forming no part of my invention.

The above parts are preferably arranged and operated in the manner described and claimed in the U. S. patent to Rhodes 95 #1,191,094, dated July 11, 1916, and as this clearly illustrates the devices whereby the thread thrower 4, awl 5 and take-up arm are actuated at the proper times, I have not shown them.

Below the thread plate 1 is mounted a vertical shaft 11 periodically oscillated through a definite arc by suitable mechanism (not shown) and having clamped to it a block 12 on which a plate 13 is guided so as to be 105 slidable in a line at right angles to the line of said shaft. For the purpose of adjusting the position of this plate, I connect to it or

provide it with a screw 14 on which is threaded a nut 15 abutting said block. Said plate 13 is extended outwardly from the block 12 and has its top edge recessed 5 for the reception of a holding awl 16, being made in two parts clamped together by a screw 17. The latter also holds to the plate 13 a second plate 18 of sheet material carried in a substantially vertical plane including the center line of the shaft 11 and having a thin finger-like prolongation 19 from its upper edge turned at right angles to its body, to constitute a thread stripper. The opening in the plate 18 for the screw 17 is 10 horizontally elongated in order to permit of a slight adjustment of said plate to vary the position of its thread-engaging extension 19.

Also operative below and through the thread plate 1 is a vertically reciprocable 20 needle 20, and as shown in Fig. 12, said plate has an opening 21 elongated in a line radial to the presser foot bar 6 in order not only to permit passage of said needle and of the awl 5 but also to allow of a lateral 25 bodily movement of the needle, from a position in line with the upper awl 5 (Fig. 9) to a position parallel with said line but nearer the line of the presser foot bar 6.

In forming a series of plugs α^1 in a sole 30 γ , the latter is placed on the thread plate 1 and the presser foot 3 is lowered in the customary manner;—the single thread α being run from the spool or bobbin through the tension mechanism to the take-up arm, 35 thence through the eye 9 of the thread guide 10, and down to the sole. If the various parts be assumed to occupy the positions shown in Figs. 6 and 7, the mechanism of the machine will operate to raise the upper 40 awl 5 out of the hole which it has just pierced in the sole γ , the needle 20 being at the lowest part of its path of movement to one side of the line of said awl. As the latter rises, the needle is laterally shifted into 45 line with the awl (Fig. 9) and it is then raised until its pointed and hooked upper end passes through the hole formed by the awl. As said needle reaches the upper limit of its stroke, the thread thrower 4 swings from 50 the position shown in Figs. 8 and 9 to that shown in Figs. 10 and 11, and its notched extension 7 engages the thread α , forming a sharp angle therein (Fig. 10). The needle 20 is thereupon moved bodily toward the 55 presser foot post 6 out of line with the awl 5, while the thread thrower dwells in its extreme displaced position, and as the needle is thereafter moved down, its hook catches the substantially horizontal portion of the 60 thread (Figs. 4 and 5), carrying it down through the sole and thread plate in an elongated loop. As this lowering of the needle occurs, the upper awl likewise moves down and ultimately engages and passes through 65 the sole to form therein another hole spaced

a predetermined distance away from that through which the thread has just been drawn.

The oscillatory spindle 11 is now turned on its vertical axis to swing the stripper finger 19 and the holding awl 16 into the thread loop just formed (Figs. 6 and 7) and the thread thrower or take up 4 retains its original position. Said take-up device then acts to pull back on the thread α which is 70 thereupon drawn taut over the stripper finger 19, while the needle 20 is moved laterally 75 out of engagement with it (Fig. 9) into line with the upper awl 5.

As said needle is raised and finally caused 80 to pass into the hole last formed in the sole, a slight angular movement of the spindle 11 causes the stripper finger 19 to disengage the thread loop, so that as the thread thrower 4 again moves into engagement with the 85 thread, it draws back the greater portion of the previously formed loop, pulling it tight over the holding awl 16 (Figs. 10 and 11). The continued turning of the spindle 11 thereafter draws this awl out of the reduced 90 thread loop, which by the action of the presser foot 3 and the lateral movement of the sole by the needle, is flattened against the plate 1 and forced into the under face of 95 said sole to constitute a head for the plug 100 just formed, (Fig. 3) while the further turning of the spindle 11 moves the stripper 105 19 and holding awl 16 into the extreme positions shown in Figs. 2 to 5 inclusive. The needle continues its upward stroke and then moves laterally into a position in which, as 110 it is lowered, its hook again engages the approximately horizontal part of the thread α held by the thread thrower 4, so that it draws a loop of thread through the second 115 formed opening in the sole. The operation of the machine thus forms a succession of uniformly spaced plugs, each of which consists of a flattened loop constituting a head and two parallel lengths extending through 120 the sole to its top surface;—adjacent plugs being connected by a single length of thread on the surface of the sole, in line with and immediately adjacent the similar superficial lengths connecting the other plugs. 115

In case of wear or when otherwise necessary, the holding awl 16 may be adjusted by turning the screw 15 so that it will project for a greater or less distance into the thread loops, and likewise by loosening the screw 120 17, the position of the stripper finger 19 may be altered at will.

From the above description it will be noted that my machine utilizes or requires 125 but a single thread in the formation of a succession of closely spaced reinforcing or filling plugs which strengthen rather than weaken the leather or other structure in which they are formed. Obviously by forming the plugs of a single length of 130

thread, I materially economize the amount thereof required for a given reinforcement and also am enabled to simplify and reduce the number of the parts of the machine required.

5 I claim:

1. The combination with the vertically reciprocating awl, thread guide, and needle of a machine of the character described of 10 a holder for temporarily engaging each loop of thread after it has been formed by the needle; a device for taking up the surplus portion of each loop; with a stripper for positively holding the thread while it is 15 being disengaged by the needle and prior to the action of the take-up device.

2. The combination in a machine of the character described of a hooked needle; means for successively placing portions of 20 a single thread in the path of movement of said needle; a stripper and a loop holding awl mounted to enter each loop of thread as it is formed by said needle; and a device for taking up the surplus of each loop to 25 cause it to close around said awl to form a headed plug.

3. The combination in a machine of the character described of mechanism for forming a single thread into a succession of 30 loops within a body of sheet material; a stripper and a loop holding awl mounted to

be introduced into each of the loops after its formation; and a device for pulling the thread of each loop tight around the awl to form a head adjacent one face of said sheet 35 material.

4. The combination in a machine of the character described of mechanism including a needle for forming a single thread into a series of loops within a body of sheet material; an oscillatory member; a stripper formed to temporarily hold each loop; a loop holding awl carried by said member in position to enter each loop after it has been formed by the needle; with mechanism 40 45 for taking up the loop held by the stripper and closing it around said awl to form a head.

5. The combination with the vertically reciprocable awl and the hooked needle of 50 a machine of the character described, of a member mounted to oscillate in a plane at right angles to the line of movement of said needle having two spaced portions positioned so that both of said spaced portions 55 enter each loop of a single thread drawn out by the needle; and mechanism for taking up the surplus of each loop to close it around one of said portions to form a head adjacent one face of the sheet material operated on. 60

In witness whereof I affix my signature.
GEORGE A. SCHICK.
